DRILLING APPARATUS

Harry C. Johansen, Michigan City, Ind., assignor
to Sullivan Machinery Company, a corporation
of Massachusetts

Application August 20, 1931, Serial No. 558,269

60 Claims. (Cl. 255—51)

This invention relates to drilling apparatus and more particularly to an improved drilling apparatus of the self-contained, portable type especially adapted for use in boring the overburden 5 for coal or similar materials.

An object of this invention is to provide an improved drilling apparatus. Another object is to provide an improved drilling apparatus especially adapted for use in boring the overburden 10 for coal or similar materials. A further object is to provide an improved drilling apparatus having improved adjustable supporting means for the boring tool whereby the latter may be positioned to drill holes at any desired angle, to drill 15 a horizontal hole close to the ground and to drill in various other positions. Yet another object is to provide an improved drilling apparatus having improved feeding and rotating mechanisms, an improved hoisting mechanism and improved 20 means for driving and operating the said mechanisms. Still another object is to provide an improved propelling means for an apparatus of the above character. A further object is to provide an improved chuck for use with such an apparatus. These and other objects and advantages 25 of the invention will, however, hereinafter more fully appear.

In the accompanying drawings there is shown for purposes of illustration one form which the 30 invention may assume in practice.

In these drawings,—

Fig. 1 is a side elevational view of the illustrative embodiment of the improved drilling apparatus.

Fig. 2 is a front end elevational view of the apparatus shown in Fig. 1.

Fig. 3 is a longitudinally extending vertical sectional view taken substantially on line 3—3 of Fig. 2 and illustrating the feeding and rotation mechanisms and the hoisting mechanism, together with the driving means therefor.

Fig. 4 is a horizontal sectional view taken substantially on line 4—4 of Fig. 3.

Fig. 5 is a vertical sectional view taken substantially on line 5—5 of Fig. 1 and illustrating the feeding and rotation mechanisms.

Fig. 6 is a transverse vertical sectional view taken substantially on line 6—6 of Fig. 1 and illustrating a portion of the apparatus in end elevation.

Fig. 7 is a detail sectional view taken substantially on line 7—7 of Fig. 6.

Fig. 8 is a horizontal sectional view taken substantially on line 8—8 of Fig. 1 and illustrating the propelling means for the apparatus.

Fig. 9 is a transverse vertical sectional view taken substantially on line 9—9 of Fig. 8.

Fig. 10 is a transverse vertical sectional view taken substantially on line 10—10 of Fig. 8.

Fig. 11 is a detail sectional view taken on line 11—11 of Fig. 3.

In this illustrative embodiment of the invention there is shown a drilling apparatus of the self-propelled, tractor tread supported and guided type generally comprising a drill rotation mechanism 1, drill feeding mechanism 2, drill hoisting mechanism 3, a fluid compressor 4 and a motor 5 for driving the various units of the apparatus. The main frame 6 of the apparatus is supported by endless traction treads 7, 7 arranged at opposite sides of the frame and between which the frame is mounted. The tractor tread supporting frames 8 are pivotally mounted at 9 at their forward ends to swing in a vertical direction relative to the main frame and are connected at their 20 rearward ends by a transverse equalizer bar 10 pivotally connected between its ends at 11 to the rear end of the main frame and at its ends to the tread frames 8, thereby providing a three-point suspension for the main frame and enabling 25 the machine to travel over uneven surfaces and obstructions. The motor 5 is suspended within the main frame and is arranged with its power shaft 12 horizontally and longitudinally disposed, as shown. 30

The fluid compressor 4 is herein of the angle cylinder or V-type and comprises cylinders 13, 13 having usual inlet and discharge valve mechanisms and discharging fluid under pressure through pipe connections 14 to a receiver tank 15 35 herein arranged transversely of the apparatus in advance of the compressor as shown in Fig. 1. The compressor driving means comprises a sprocket 16 journaled on the rearwardly projecting end of the motor shaft 12 and connectible to 40 the motor shaft by a usual jaw clutch 17. The sprocket 16 is connected by a multiple chain connection 18 to a sprocket 19 suitably fixed to the compressor crank shaft 20. The jaw clutch 17 is operated by a pivoted shipper lever 21, as shown 45 in Fig. 1. The cylinders 13, 13 of the compressor are provided with usual water jackets supplied with cooling water from a radiator 22 mounted at the rear of the apparatus. The sprocket 19 secured to the compressor crank shaft has rotat- 50 able therewith and driven thereby a pulley 23 connected by an endless belt 24 to a fan pulley 25, and this latter pulley drives a pump shaft 26 of a pump 27 which circulates cooling fluid from the radiator through pipe connections 28 to the cyl- 55

nder water jackets. The cooling fluid is conducted from the cylinder water jackets to the upper end of the radiator through pipe connections 29. As is usual in compressors of the type disclosed, the load on the compressor is controlled by the receiver pressure through a usual pilot valve and inlet valve unloading mechanism, but as such accessories are well known to those skilled in the art, description and illustration of the same are thought unnecessary.

Now referring to the improved driving connections for the drill rotation mechanism 1, it will be noted that keyed to the rear end of the motor power shaft adjacent the sprocket 16 is a chain sprocket 30 connected by an endless chain 31 to a sprocket 32 keyed to the rear end of a counter-shaft 33 herein arranged parallel with the motor shaft and extending alongside and suitably journaled on the main frame. Keyed to the forward end of this counter-shaft is a chain sprocket 34 connected by an endless chain 35 to a sprocket 36 keyed to the rear end of a longitudinal drive shaft 37. This shaft is suitably journaled on the machine frame in the manner shown in Fig. 3 and is connectible by a multiple disc clutch 38 to an alined shaft 39 of a change speed or selective gear shift mechanism 40. The operating means for the clutch 38 comprises a clutch applying member 41 slidably mounted on the shaft 37 and operating through pivoted fingers 42 a pressure plate 43 acting on the clutch discs. Connected to the member 41 is a shipper yoke 44 having a pivoted operating lever 45. As illustrated, the shaft 39 of the change speed mechanism 40 has splined thereto at 46 a sleeve 47 having integrally connected therewith gears 48 and 49 of different size. Arranged parallel with the shaft 39 and suitably journaled within the drill base 50 is a shaft 51 having keyed thereto gears 52 and 53 of different size and with which the gears 48, 49 are adapted selectively to mesh. With the gears 48, 52 are in mesh, the shaft 51 is driven at a relatively high speed, and when the gears 49, 53 are in mesh the shaft 51 is driven at a relatively slow speed. The shiftable change speed gears 48, 49 are operated by a shipper yoke 54 fixed to a slideable operating rod 55 actuatable through a rack and pinion 56 by a lever 57. As shown in Fig. 3, the shaft 51 is arranged with its axis alined with a frame 58 attached to the drill base and on which is mounted for swinging movement about the axis of shaft 51 a radial arm or extension frame 59. Mounted on the outer end of the arm 59 for swinging movement about an axis parallel with the arm axis is a swivel head 60. Fixed to the forward end of the shaft 51 is a chain sprocket 61 connected by a multiple chain connection 62 housed in the arm 59 to a chain sprocket 63 keyed to a shaft 64 arranged with its axis coincident with the swivel head axis. Keyed to the forward end of the shaft 64 is a bevel gear 65 meshing with a bevel gear 66 keyed to a rotation sleeve 67 suitably journaled on the swivel head frame 68. Extending centrally through and splined at 69 to the rotation sleeve 67 is a hollow drive rod 70. Extending centrally through the hollow drive rod and connectible to the drive rod for rotation therewith by a chuck generally designated 71 is a usual drill stem 72. It will thus be seen that the drill stem may be rotated by the motor 5 at a plurality of speeds.

The mechanism for swinging the arm or extension frame 59 and for swivelly mounting the swivel head 60 on the outer extremity of the arm will now be described. Herein formed integral with the frame 58 is a worm wheel 73 with

which meshes a worm 74 keyed to a transverse shaft 75 suitably journaled within brackets 76 attached to the arm 59. The ends of the shaft 75 are squared for the reception of a suitable turning instrument, herein a detachable handle 77 shown in Fig. 1. It will thus be seen that the arm 59 may be swung about the axis of the shaft 61 into any desired angular position, and is automatically locked in such position by the self-locking teeth of the worm gearing 73, 74. The outer extremity of the arm 59 is provided with an annular flange 78 having a cylindrical projection 79 presenting an annular bearing surface on which is rotatably mounted a swivel frame 80. The frame 80 is annularly grooved at 81 to receive the heads of holding bolts 82. Pivotally mounted at 83 on lateral lugs formed integral with the swivel frame 80 is the swivel head 60, the swivel head being swingable about its hinged connection with the swivel frame outwardly into the position indicated in dotted lines in Fig. 4, for purposes well understood to those skilled in the art. The swivel frame is held in its operative position, with the bevel gears 65, 66 maintained in meshing engagement, by a bolt 84 pivoted at 85 on the swivel head frame and engageable with a slot 86 formed in the lateral edge of the frame 80. The bolt 84 is provided with a usual tightening nut 87. It will thus be seen that when the holding bolts 82 are loosened, the swivel head may be swung into any desired angular position about the axis of the shaft 64, and may be secured in any of its adjusted positions by suitable tightening these holding bolts.

Now referring to the drill feeding means 2, it will be observed that mounted on the swivel head frame 68 are parallel feed cylinders 88, 88 containing reciprocable feed pistons 89, 89. These feed pistons are provided with parallel piston rods 90, 90 rigidly connected at 91 to a thrust head frame 92. This frame carries a usual thrust bearing 93 for receiving the axial thrust of the drive rod. Pressure fluid may be supplied to the opposite ends of the feed cylinders through pipe connections 94 controlled by usual valves 95, 95, and fluid under pressure is supplied to these pipe connections under the control of a throttle valve 96 through a hose 97 connected to the receiver 15 through a valve controlled connection 98. It will thus be seen that upon suitable manipulation of the control valves, the drive rod may be fed upwardly and downwardly, as desired. Carried at the upper end of the drill stem 72 is a usual fluid swivel 99 connected, through a hose connection 100 controlled by a valve 101, to the receiver 15. It will thus be seen that pressure fluid may be supplied from the compressor receiver through the hose connections above described to operate the feeding mechanism and to supply cleansing fluid through the drill stem to the boring tool 102 carried at the lower end of the drill stem, thereby to blow out the cuttings from the bottom of the drill hole.

The chuck 71 for connecting the drill stem 72 to the drive rod 70 herein comprises a casing 103 threadedly connected at 104 to the drive rod, and contained in this casing are wedge-like chuck jaws 105, herein four in number, each having an adjusting screw 106. Arranged between each of the adjusting screws and the chuck jaws is a coiled spring 107 for constantly urging the chuck jaws into their gripping position. For moving and holding the chuck jaws in their released position is a member 108 threadedly connected

at 109 to the chuck casing and held in its different adjusted positions by a spring pressed plunger lock 109. The member 108 engages plunger rods 110 slidably guided in the chuck casing and engaging at 111 the chuck jaws. It will thus be seen that when the drive rod is fed relative to the drill stem the chuck jaws 105 grip automatically the drill stem, and when the drive rod is fed in the opposite direction, the chuck jaws automatically release. The screws 106 may be adjusted to move the chuck jaws into a position to grip positively the drill stem so that the drill stem may be fed in either direction without release of the jaws.

15 The hoisting mechanism 3 comprises a hoisting drum 112 arranged on a longitudinal axis and having wound thereon, as shown in Fig. 1, a usual hoisting cable 113. This cable 113 extends upwardly from the hoisting drum around 20 a top pulley 114, and the drop line of this cable carries a swivel hook 115 connectible to the fluid swivel 99 of the cleansing fluid supply connection. The top pulley is supported on the main frame by standards 116, braced by brace rods 117 in the usual manner. The means for driving the hoisting drum comprises a spur gear 118 splined to the shaft 51, as shown in Fig. 3, and the means for sliding the gear 118 comprises a pivoted shipper yoke 119 operated by a lever 120.

25 The gear 118 is adapted to mesh with an idler gear 121 journaled on a shaft 122 suitably supported by a hoist frame 123 and the gear 121 meshes with a spur gear 124 keyed to the drum shaft 125. Also keyed to the shaft 125 is a spur gear 126 meshing with a spur gear 127. Rotatable with and driven by the gear 127 is a spur gear 128 which meshes with a gear 129. The gear 129 meshes with an internal gear 130 secured to a rotatable reaction member 131 controlled by a brake band 132. The hoisting drum is provided with a usual brake band 133. It will thus be seen that when the gear 118 is in meshing engagement with the gear 121 and the reaction member 131 is held stationary by the brake band 132, the hoisting drum 112 is driven through the gears 124, 126, 127, 128, and 129, the last of which meshes with and rolls around as on a trackway, the internal gear 130. When the brake band 132 is released and the brake band 133 is applied, the hoisting drum 112 is held stationary.

30 The mechanism driven by the motor 5 for driving the endless traction treads 7, 7 for propelling and guiding the apparatus is substantially the same in structure and operation as that described and claimed in the patent to Frank A. Halleck, No. 1,771,625, patented July 29, 1930. This drive mechanism comprises a spur gear 135 fixed to the forward end of the motor shaft 12 and meshing with a spur gear 136 connected to a longitudinal shaft 137. Connectible to the shaft 137 by a multiple disc clutch 138 is a spur gear 139 meshing with spur gears 140, 141. Meshing with the spur gear 141 is a spur gear 142; and the gear 141 has a greater number of teeth than either of the gears 140, 142, which have the same number of teeth, the purpose of which will be hereinafter fully described. The gears 140, 141, 142 are connectible by multiple disc clutches 143, 144, 145 respectively to longitudinal shafts 146, 147 and 148. Coaxial with the shafts 146, 147 and 148 and driven by the gears 140, 141 and 142 are worms 149, 150 and 151. The shafts 146, 147 and 148 are adapted to be held against rotation by brake frictions 152, 153 and 154 re-

spectively. The worms 149, 150 and 151 mesh respectively with worm wheels 155, 156 and 157 which are adapted to drive, through differentials 158 and 159, alined shafts 161 and 162, one connected in driving relation with each traction tread as shown in Fig. 10. Each differential includes coaxial bevel gears 163, 164 with which mesh planet gears 165 carried by a spider member 166 keyed to the alined shaft 161 or 162. The clutch and brakes for each worm are operated by 10 an applying member 167 slidably mounted on the worm shaft and operated by a shipper member 168. The applying member is provided with cam surfaces 169 which are engageable with levers 170; and when the member is shifted in one direction 15 the clutch is applied and the brake released, and when shifted in the opposite direction the brake is applied and the clutch released. As shown in Fig. 9, the shipper members 168 are actuated by rods 171, 172 and 173 respectively; and these rods 20 are operated through cranks, links and pull rods by control levers 174 and 175 pivotally mounted on the side of the machine frame, as shown in Fig. 1. As the operating means for the worm clutches and brakes are clearly described in the 25 above mentioned patent, further description of the same herein is thought unnecessary other than to state that the brakes and clutches for each worm are independently controllable to effect drive of the worms separately or simultaneously. It is to be noted that the worms 149, 150 and 151 have the same pitch, but that the worms 149 and 151 on the shafts 146 and 148 are right and left hand respectively. The worm wheel 156 is driven in a direction opposite to that 30 in which the worm wheels 155 and 157 are driven, due to the fact that one side of the gear 139 meshes with the gear 140, while the other side meshes with the gear 141, thus driving gears 140 and 141 in the same direction, while gear 142 will 40 rotate in a direction opposite to the gear 140, but the worm wheels driven thereby will rotate in the same direction due to the right and left hand worms 149 and 151.

45 If it is desired to feed the apparatus forwardly at a relatively fast speed, the brakes on shafts 146 and 148 are released and the clutches 143, 145 are applied, connecting the worms 149, 151 and their respective shafts 146, 148 to the gears 140 and 142 respectively. During such operation, 50 the brake on shaft 147 is applied and the clutch 144 released; thus the worm 150 on shaft 147 is held against rotation and consequently rotation of the worm wheel 156 is prevented. The worm wheel 156 in turn prevents rotation of the inner 55 bevel gears of the differentials; and inasmuch as the shafts 146 and 148 are now oppositely driven, due to the clutch engagement, worm wheels 155 and 157 are driven by the worms 149 and 151 respectively to cause rotation of the planetary 60 bevel pinions orbitally around the stationary bevel gears which then act as reaction gears. The spider members of the differentials will thereby be oppositely carried around by the planet gears to cause a positive rotation of the 65 alined shafts 161, 162. If, however, it should be desired to turn the apparatus in one direction or the other, one of the shafts 146 or 148 would be held stationary while the other reverse shaft 147 is also being held, this allowing movement of only 70 one traction tread or the desired fractional movement thereof. If it is desired to impart fast reverse movement to the apparatus, shafts 146 and 147 will be held stationary by their respective brakes, while the clutches thereon are released 75.

and the reverse mechanism actuated by applying the clutch 144 mounted on the shaft 141 and releasing the shaft brake to drive positively the shaft 147, which in turn will drive the worm wheel 156 in a reverse direction to drive the planet gears in a reverse direction around the outer bevel gears of the differential, which are now held stationary by the held or stationary shafts 146 and 148. If it is desired to propel the apparatus at a relatively slow speed, all the brakes on shafts 146, 147 and 148 are released and the clutches therefor are simultaneously applied, connecting the worms 149, 150 and 151 and their shafts 146, 147 and 148 to the gears 140, 141 and 142 respectively for rotation therewith. This, it will be seen, simultaneously operates both the fast reverse and fast forward feed mechanisms, and due to the differential action between the same a slow forward speed is obtained, the slow forward feed being obtained due to the fact that the gear 141 has a greater number of teeth than either the gear 140 or gear 142 so that the worm wheel 156 has a slightly smaller angular velocity than do the wheels 155 and 157. The smaller angular velocity of the gear 141, and consequently of the worm 150 and worm wheel 156 in the reverse feed, is due to the fact that the ratio of the gear 141 to the motor driving pinion 135 is greater than the ratio of the gears 140 and 142 to said motor driving pinion. Thus, during the slow forward movement, the worm wheel 156 drives the planet gears of the differential oppositely and at a slower speed than do the worm wheels 155 and 157, the result being that the spider members of the differentials will take a slow forward speed equal to the difference between the speed of the respective bevel gears meshing with the bevel planet gears, and thus will drive the aligned shafts 161, 162 at a slow forward speed. It is therefore obvious that the slow forward speed is obtained by the simultaneous operation of a fast reverse and fast forward feeds. As the operation of the propelling means for the apparatus is clearly described in the above mentioned Halleck patent, a further description thereof is herein unnecessary.

In the use of the improved apparatus, it will be noted that when the clutch 17 is connected, the compressor 4 may be driven by the motor 5 through the chain and sprocket connections 16, 18 and 19 connected to the compressor crank shaft 20. The compressor discharges fluid through pipe connections 14 to the receiver 15, from which fluid is supplied through hose connection 97 to the drill feeding mechanism and through hose connection 100 to the hole cleansing means. When the multiple disc clutch 38 is applied and the shiftable gears 48, 49 of the change speed mechanism are suitably connected to gears 52 or 53, the drill rotation mechanism may be driven by the motor 5 through the chain and sprocket connection 30, 31, 32, counter-shaft 33, chain and sprocket connection 34, 35, 36, shaft 37, the change speed gearing, shaft 51, chain and sprocket connection 61, 62, 63 and bevel gearing 65, 66. By suitably connecting the gear 118 in meshing engagement with the gear 121 and applying the brake band 132, the hoisting drum 112 may be driven through the change speed mechanism at a plurality of speeds. The swivel head 60 of the drill may be adjusted into any desired angular position on the outer extremity of the arm 59 by suitably loosening the bolts 82 and turning the swivel head in its bearing, the bolts thereafter being tightened to hold the swivel head in posi-

tion. The arm 59 may be swung into any desired position about its axis by simply turning the worm gears 73, 74. The chuck 71 may be operated by suitably manipulating the control elements 106 and 108. During the drilling operation, the hoisting cable 113 is extended upwardly from the hoisting drum around the top pulley 114, and the drop line of the cable is connected by the hook 115 to the fluid swivel 99, thereby enabling the drill stem 12 to be raised, lowered or held suspended, as desired. The drill rotation mechanism is then connected to the motor and the drive rod 70 is rotated. Pressure fluid is supplied from the receiver 15 to the feed cylinders 88, 88 under the control of the valves 95, 96, thereby moving the feed pistons 89, 89 downwardly. As the feed pistons move downwardly, the chuck jaws 105 of the chuck 71 grip automatically the drill stem, thereby connecting the drill stem to the drive rod and feeding mechanism, and as a result, as the drill stem is fed downwardly, it is rapidly rotated. During the drilling operation pressure fluid is supplied from the receiver 15 through the hose connection 100, fluid swivel 99 and the hollow drill stem to the boring tool 102 to cleanse the cuttings from the latter. When pressure fluid is supplied to the opposite ends of the feed cylinders, the driving rod and chuck are fed forwardly, and as a result, the chuck jaws 105 are released automatically from their gripping engagement with the drill stem. If it is desired to effect feed of the drill stem positively in either direction, the chuck jaws 105 are moved into positive gripping engagement with the drill stem by suitable adjustment of the screws 106, and the chuck jaws may be held entirely released by suitable adjustment of the member 108. The machine may be propelled either forwardly or rearwardly at a relatively high speed or forwardly at a relatively slow speed, as desired, through the differential connections 40 driven by the motor 5. It will be noted that by suitable adjustment of the swivel head and swingable arm 59, the drill may be operated to drill holes in any desired angular position, in horizontal positions adjacent the ground, in parallel vertical positions at either side of the apparatus, or any desired intermediate positions, thereby enabling the drill to be readily adjusted to accommodate itself to varying drilling conditions.

As a result of this invention, it will be noted that an improved drilling apparatus is provided which is entirely self-contained, the various mechanisms of the machine being mounted on a portable base of the self-propelled type and driven from the power unit on the base. It will further be noted that the motor 5 drives the various units of the apparatus, and that the fluid compressor 4 supplies fluid to both the feeding means and hole cleansing means. It will further be noted that the various mechanisms of the machine are arranged in an improved compact manner on the base, thereby resulting in an apparatus which is extremely well balanced, compact and readily portable from one working place to another. These and other uses and advantages of the improved drilling apparatus will be clearly apparent to those skilled in the art.

While I have in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a drilling apparatus, a base, a drilling tool, and adjustable supporting means on said base for said drilling tool including a swingable arm pivoted on an axis extending longitudinally of said base midway between the sides of said base and means for adjustably mounting said drilling tool on said arm, said arm being swingable about said axis and said mounting means adjustable relative to said arm to adjust said drilling tool into any desired horizontal drilling position between a bottom drilling position and a top drilling position and any desired vertical drilling position between the sides of said base.

2. In a drilling apparatus, a base, adjustable supporting means mounted on said base including an arm mounted to swing in transverse planes about a horizontal axis, and a swivelled drill head pivotally mounted on the outer extremity of said arm, said arm being swingable about said horizontal axis while the latter remains fixed with respect to said base and the drill head pivot always remains parallel to a common straight line to adjust said drill head into drilling positions at either side of said base.

3. In a drilling apparatus, a base, an arm mounted on said base to swing about a horizontal axis extending longitudinally of said base, and a swiveled drill head mounted on the outer extremity of said arm for swinging movement about a parallel axis, said arm being swingable about said horizontal axis while the latter remains fixed to position the drill head in drilling positions at either side of said base and said drill head being swingable about said parallel axis in any position of said arm.

4. In a drilling apparatus, a base, an arm mounted on said base to swing in transverse planes relative thereto about a horizontal axis, a swiveled drill head mounted on said arm for swinging movement relative thereto about a parallel axis, and drill feeding mechanism carried by said swiveled drill head, said arm being swingable about said horizontal axis while the latter remains fixed to position said drill head in drilling positions at either side of said base and said drill head being swingable about said parallel axis in any position of said arm.

5. In a drilling apparatus, a base, a drilling tool, an adjustable supporting structure on said base for said drilling tool for adjusting the latter in transverse vertical planes relative to said base into any desired lateral drilling position across said base from one side of the latter to the other while said drilling tool always remains in aforesaid transverse vertical planes, a motor on said base relative to which said supporting structure is adjustable, and mechanism driven by said motor for rotating said drilling tool.

6. In a drilling apparatus, a base, a drilling tool, an adjustable supporting structure on said base for said drilling tool for adjusting the latter in transverse vertical planes relative to said base into any desired lateral drilling position across said base from one side of the latter to the other while said drilling tool always remains in aforesaid transverse vertical planes, a motor on said base relative to which said supporting structure is adjustable, and mechanism driven by said motor for rotating said drilling tool irrespective of the adjusted position of said supporting structure relative to said base.

7. In a drilling apparatus, a base, a motor on said base having its power shaft horizontally and

longitudinally disposed, drill rotation mechanism driven from one end of said motor, drill feeding mechanism, a fluid compressor driven from the same end of said motor for supplying fluid under pressure to said feeding mechanism, and mechanism driven from the opposite end of said motor for propelling said base. 5

8. In a drilling apparatus, a base, an elongated arm mounted on said base to swing in transverse vertical planes relative to said base about a horizontal axis, mechanism for swinging said arm and for holding said arm in its different angular positions about said horizontal axis relative to said base, a drilling mechanism, and means for mounting said drilling mechanism on the outer 10 extremity of said arm, said arm being swingable about said horizontal axis and said mounting means adjustable relative to said arm to move the drill mechanism across said base from one side thereof to the other into positions to drill 15 holes in any desired location between the sides of said base in planes parallel to the planes of swinging movement of said arm.

9. In a drilling apparatus, a base, an arm mounted on said base to swing from one side 25 thereof to the other in transverse planes relative thereto about a horizontal axis located midway between the sides of said base, mechanism for swinging said arm about said axis and for holding said arm in its different angular 30 positions relative to said base, and a drill feeding mechanism mounted on the outer extremity of said arm to swing relative to said arm about a parallel axis.

10. In a drilling apparatus, a base, an elongated arm mounted on said base to swing relative thereto about an axis extending longitudinally of said base, a drilling mechanism, and means for mounting said drilling mechanism on the outer extremity of said arm, said arm being swingable 40 about said longitudinal axis and said mounting means adjustable relative to said arm to move said drilling mechanism across said base into positions to drill holes at any desired location between the sides of said base and at either side 45 of said base in planes parallel to the planes of swinging movement of said arm.

11. In a drilling apparatus, a base, an arm mounted on said base to swing relative thereto, and a drilling mechanism swivelly mounted to 50 swing about a longitudinal axis on the outer extremity of said arm, said arm being swingable relative to said base to position the drilling mechanism in drilling position at either side of said base while said longitudinal axis always remains 55 parallel to a common straight line.

12. In a drilling apparatus, a base, an arm mounted on said base to swing in transverse planes relative thereto, and a drilling mechanism swivelly mounted on the outer extremity of said 60 arm about an axis parallel to the arm pivot axis, said arm being swingable about its pivotal axis relative to said base to position the drilling mechanism in drilling position at either side of said base while said parallel axis always remains parallel to a common straight line.

13. In a drilling apparatus, a base, a drilling tool, adjustable supporting means on said base for adjusting the tool about a longitudinal axis into different lateral positions relative to said base, 70 fluid operated feeding means for the drilling tool, and a fluid pump on said base and relative to which the tool is adjustable for supplying fluid under pressure to said feeding means.

14. In a drilling apparatus, a portable base, an 75

arm pivotally mounted on said base at one end thereof to swing relative thereto about an axis extending longitudinally of said base, said arm being swingable about said axis into horizontal

- 5 positions wherein the outer extremity thereof extends laterally from the sides of the base, and a drilling tool carried on the outer extremity of said arm, said arm being swingable as aforesaid about said longitudinal axis to move said drilling 10 tool into any desired position between the sides of said base to drill a series of parallel vertical holes between the sides of said base.

15. In a drilling apparatus, a portable base, an arm pivotally mounted on said base at one end thereof to swing relative thereto about an axis extending longitudinally of said base, said arm being swingable about said axis into horizontal 20 positions wherein the outer extremity thereof extends laterally from the sides of the base, and a drilling tool swivelly mounted on the outer extremity of said arm, said arm being swingable as aforesaid about said longitudinal axis to adjust the drilling tool into parallel vertical drilling 25 positions while said tool swivel axis always remains parallel to a common straight line, and said tool being swingable about its swivel axis relative to said arm in any position of said arm.

16. In a drilling apparatus, a portable base, an arm pivotally mounted on said base at one end thereof to swing relative thereto about a longitudinal axis, said arm being swingable about said axis into horizontal positions wherein the outer extremity thereof extends laterally from the sides of the base, and a drilling tool swiveled on the outer extremity of said arm to swing about an axis parallel with the arm pivot axis, said arm being swingable as aforesaid about said longitudinal axis to position the drilling tool into parallel vertical drilling positions and said tool being 40 swingable about its parallel axis in any position of said arm.

17. In a drilling apparatus, a portable base, a swiveled drill head rotatable about a longitudinal axis, an adjustable supporting structure on said 45 base on which said drill head is swivelly mounted for adjusting the drill head in transverse planes bodily into different elevations relative to the base, said drill head being swingable about its swivel axis into positions to drill holes at either 50 side of said base in any of the aforesaid elevated positions.

18. In a drilling apparatus, a portable base, a horizontal motor on said base having its power shaft extending longitudinally of said base, a 55 drilling tool mounted on said base at one end thereof and including drill feeding and rotation mechanisms, a fluid compressor mounted on the opposite end of said base for supplying fluid under pressure to the drill feeding mechanism, driving connections between said fluid compressor and the adjacent end of said motor, and driving connections between the end of said motor remote from said drilling tool and the drill rotation mechanism.

19. In a drilling apparatus, a portable base, a horizontal motor on said base having its power shaft extending longitudinally of said base, a 60 drilling tool mounted on said base at one end thereof and including drill feeding and rotation mechanisms, a fluid compressor mounted on the opposite end of said base for supplying fluid under pressure to the drill feeding mechanism, driving connections between said fluid compressor and the adjacent end of said motor, driving connections between the same end of said motor and

the drill rotation mechanism, and mechanism driven from the opposite end of said motor for propelling the base.

20. In a drilling apparatus, a portable base, a horizontal motor on said base having its power shaft extending longitudinally of said base, a 5 drilling tool mounted on said base at one end thereof and including drill feeding and rotation mechanisms, a fluid compressor mounted on the opposite end of said base for supplying fluid under pressure to the drill feeding mechanism, a 10 drill hoisting mechanism mounted on said base between said fluid compressor and said drilling tool, driving connections between said fluid compressor and the adjacent end of said motor, and 15 driving connections between the end of said motor remote from said drilling tool and the drill rotation mechanism and said hoisting mechanism.

21. In a drilling apparatus, a portable base, a 20 horizontal motor on said base having its power shaft extending longitudinally of said base, a 25 drilling tool mounted on said base at one end thereof and including drill feeding and rotation mechanisms, a fluid compressor mounted on the 30 opposite end of said base for supplying fluid under pressure to the drill feeding mechanism, a 35 drill hoisting mechanism mounted on said base between said fluid compressor and said drilling tool, driving connections between said fluid compressor and the adjacent end of said motor, driving 40 connections between the same end of said motor and the drill rotation mechanism and said hoisting mechanism, and mechanism driven from the opposite end of said motor for propelling the 45 base.

22. In a drilling apparatus, a portable base, a drilling tool swiveled to swing about a longitudinal axis and including drill rotation mechanism, an adjustable supporting structure for the drilling 50 tool and including supporting means mounted to swing about a horizontal axis on said base for bodily adjusting the drilling tool into different elevated positions with its swivel axis in different horizontal planes, said drilling tool being 55 swingable about its swivel axis in any of aforesaid elevated positions relative to said supporting structure into positions to drill holes at either side of said base, a motor on said base relative to which the drilling tool is adjustable, and means 60 driven by said motor for driving the drill rotation mechanism in any adjusted position of said drilling tool.

23. In a drilling apparatus, a portable base, a drilling tool mounted on said base to swivel about 55 an axis extending longitudinally of said base, and an adjustable supporting structure for said drilling tool and including supporting means mounted to swing about a horizontal longitudinal axis on said base with respect to the latter for bodily 60 adjusting said swivel axis into different elevated positions relative to said base to position the drilling tool to drill holes in advance of the base in planes above and below a horizontal plane including said supporting means axis.

24. In a drilling apparatus, a portable base, a drilling tool mounted on said base to swivel about a longitudinal axis, and an adjustable supporting structure for the drilling tool and including supporting means mounted to swing about a horizontal axis on said base for bodily adjusting the swivel axis of the tool into different elevated positions relative to the said base while said swivel axis always remains parallel to a common straight line during such adjustment, said drilling tool 75

- being adjustable as aforesaid to drill holes in planes above and below a horizontal plane including said supporting means axis and in advance of said base in such planes.
25. In a drilling apparatus, a portable base, a drilling tool mounted on said base to swing about an axis extending longitudinally of said base, and an adjustable supporting structure for said drilling tool for bodily adjusting the axis of swing of the latter into different elevations and laterally relative to said base at either side of said base while said drilling tool is maintained against bodily movement in a direction longitudinally of said base.
26. In a drilling apparatus, a portable base, a drilling tool mounted on said base to swing about a longitudinal axis, and an adjustable supporting structure for the drilling tool for bodily adjusting the axis of the latter into different elevated positions and laterally relative to the said base at either side of said base with its swivel axis always parallel to a common straight line during such adjustment.
27. In a drilling apparatus, a portable base, a motor on said base, a drilling tool, adjustable supporting means on said base for said drilling tool and on which the tool is adjustably mounted, said supporting means including a hollow arm swingably mounted upon the base and on the outer extremity of which said drilling tool is swivelly mounted, said arm being swingable in transverse vertical planes with respect to said base to adjust said drilling tool into drilling positions at either side of said base while said arm is maintained in said transverse vertical planes and while the swivel axis of said tool always remains parallel to a common straight line, and driving connections between said motor and said drilling tool including transmission means housed within said arm.
28. In a drilling apparatus, a portable base, a motor on said base, a drilling tool, adjustable supporting means on said base for said drilling tool and on which the tool is adjustably mounted, said supporting means including a hollow arm swingably mounted upon the base and on the outer extremity of which said drilling tool is swivelly mounted, said arm being swingable in transverse vertical planes with respect to said base and motor to adjust said drilling tool into drilling positions at either side of said base while said arm is maintained in said transverse vertical plane and while the swivel axis of said tool remains always parallel to a common straight line, and driving connections between said motor and said drilling tool including a transmission element alined with the arm pivot axis, a transmission element alined with the drill swivel axis, and connections between said transmission elements housed in said arm.
29. In a drilling apparatus, a portable base, a motor on said base, a swivel drill head, an adjustable supporting structure for said drill head and on which said drill head is swiveled on an axis extending longitudinally of said base, said supporting structure including supporting means swingable about a horizontal axis on said base through at least 180° adjustable to position the drill head into different elevated positions relative to the base and said motor including drilling positions in planes above and below a horizontal plane including the horizontal axis of said supporting means, and driving connections between said motor and said drill head operative irrespective of the adjusted position of the drill head.
30. In a drilling apparatus, a portable base, a motor on said base, a swivel drill head, an adjustable supporting structure for said drill head and on which said drill head is swiveled on an axis extending longitudinally of said base, said supporting structure being adjustable to position the drill head into different elevated positions relative to the base and said motor including drilling positions in planes above and below a horizontal plane including the horizontal axis of said supporting means, and driving connections between said motor and said drill head operative irrespective of the adjusted position of the drill head and including a longitudinally extending shaft driven by said motor, a parallel shaft alined with the drill head swivel axis, and adjustable connections between said shafts.
31. In a drilling apparatus, a portable base, a motor on said base, a swivel drill head, an adjustable supporting structure for said drill head and on which said drill head is swiveled on an axis extending longitudinally of said base, said supporting structure being adjustable to position the drill head into different elevated positions relative to the base and said motor, and driving connections between said motor and said drill head operative irrespective of the adjusted position of the drill head and including a longitudinally extending shaft arranged along one side of the base and driven by said motor, a parallel shaft driven by said first shaft, a shaft driven by said parallel shaft and alined with the drill head swivel axis, and adjustable driving connections between said last two mentioned shafts.
32. In a drilling apparatus, a portable base, a motor on said base, a swivel drill head, an adjustable supporting structure for said drill head and on which said drill head is swiveled on an axis extending longitudinally of said base, said supporting structure being adjustable to position the drill head into different elevated positions relative to the base and said motor, and driving connections between said motor and said drill head operative irrespective of the adjusted position of the drill head and including a longitudinally extending shaft arranged along one side of the base and driven by said motor, a parallel shaft, a third shaft, a fourth shaft alined with the swivel head axis, and adjustable driving connections between said third and fourth mentioned shafts.
33. In a drilling apparatus, a portable base, a motor on said base, a swivel drill head, an adjustable supporting structure for said drill head and on which said drill head is swiveled on an axis extending longitudinally of said base, said supporting structure being adjustable to position the drill head into different elevated positions relative to the base and said motor, and driving connections between said motor and said drill head operative irrespective of the adjusted position of the drill head and including a longitudinally extending shaft arranged along one side of the base and driven by said motor, a parallel shaft, a third shaft, a fourth shaft alined with the swivel head axis, and adjustable driving connections between said third and fourth mentioned shafts and a change speed mechanism between said second and third mentioned shafts.
34. In a drilling apparatus, a base, a boring tool, and adjustable supporting means on said base for said boring tool for adjusting the latter relative to the base into any desired vertical boring position between the sides of said base and into any desired horizontal boring position

- between a low horizontal boring position and a high horizontal boring position, the longitudinal axis of the boring tool in all the aforesaid boring positions lying in a common vertical plane 5 extending transversely of said base, and a motor mounted on said base and relative to which said boring tool is adjustable for driving said boring tool irrespective of its adjusted position.
35. In a drilling apparatus, a portable base, 10 drill rod rotation and feeding mechanism swiveled on said base about an axis extending longitudinally of said base, mechanism including supporting means adjustable about a horizontal axis on said base through more than 180° for adjusting the elevation of said swivel axis relative to said base to position said mechanism to drill holes in planes above and below the horizontal plane including the horizontal axis of said supporting means, and mechanism on said base for 15 driving said drill rod rotation mechanism irrespective of the adjusted position of said swivel axis relative to said base.
36. In a drilling apparatus, a portable base, 20 drill rod rotation and feeding mechanism swiveled on said base about an axis extending longitudinally of said base, mechanism for adjusting the elevation and lateral position of said swivel axis relative to said base operative to position the drill at opposite sides of the longitudinal center of the base while the longitudinal axis of 25 said mechanism at all times lies in a common vertical plane extending transversely of said base, said adjusting mechanism being adjustable as aforesaid to position the drill mechanism to drill parallel horizontal holes and parallel vertical holes, and mechanism on said base for driving said 30 drill rod rotation mechanism irrespective of the adjusted position of said swivel axis relative to said base.
40. 37. In a drilling apparatus, a portable base, 35 drill rod rotation and feeding mechanism swiveled on said base about an axis extending longitudinally of said base, mechanism for adjusting the elevation of said swivel axis relative to said base to position the drill mechanism to drill holes between a position near the ground surface and a position a substantial distance above said base, mechanism on said base for driving said 40 drill rod rotation mechanism irrespective of the adjusted position of said swivel axis relative to said base, and mechanism on said base and relative to which the swivel axis of said drill rod rotation and feeding mechanism is adjustable for operating said feeding mechanism.
55. 38. In a drilling apparatus, a portable base, 45 drill rod rotation and feeding mechanism swiveled on said base about an axis extending longitudinally of said base, mechanism for adjusting the elevation and lateral position of said 50 swivel axis relative to said base to position said drill mechanism to drill holes between a position near the ground surface and a position a substantial distance above said base and at either side of said base, mechanism on said base for driving said 55 drill rod rotation mechanism irrespective of the adjusted position of said swivel axis relative to said base, and mechanism on said base and relative to which the swivel axis of said drill rod rotation and feeding mechanism is adjustable for operating said feeding mechanism.
60. 39. In a drilling apparatus, a portable base, 60 drill rod rotation and feeding mechanism swiveled on said base about an axis extending longitudinally of said base, mechanism including supporting means adjustable about a horizontal axis on said base through at least 180° for adjusting the elevation of said swivel axis relative to said base while said swivel axis always remains parallel to a common straight line extending longitudinally of the apparatus, said supporting means being adjustable as aforesaid to position the drill mechanism to drill holes between a position near the ground surface and a position a substantial distance above said base, and mechanism on said base for driving said 65 drill rod rotation mechanism irrespective of the adjusted position of said swivel axis relative to said base.
40. In a drilling apparatus, a portable base, 70 drill rod rotation and feeding mechanism swiveled on said base about an axis extending longitudinally of said base, supporting means including mechanism for adjusting the elevation and lateral position of said swivel axis relative to said base while said swivel axis always remains parallel to a common straight line extending longitudinally of the apparatus, said supporting means being adjustable as aforesaid to position the drill mechanism to drill holes between a position near the ground surface and a position a substantial distance above said base and at either side of said base, and mechanism on said base for driving said 75 drill rod rotation mechanism irrespective of the adjusted position of said swivel axis relative to said base.
41. In a drilling apparatus, a portable base, a frame mounted on said base for rotation about an axis extending longitudinally of said base, mechanism including supporting means swingable relative to said base for adjusting said frame into different elevated positions relative to said base in advance of the latter while maintaining said longitudinally extending axis continuously parallel to a common straight line, and drill rod rotation and feeding mechanisms mounted on said 80 rotatable frame, said supporting means being adjustable as aforesaid to position the drill mechanism to drill holes in planes above and below a horizontal plane including the supporting means axis.
42. In a drilling apparatus, a portable base, a frame mounted on said base for rotation about an axis extending longitudinally of said base, mechanism for adjusting the elevation and lateral position of said frame relative to said base while said frame is maintained against bodily movement in a direction longitudinally of said base, and drill rod rotation and feeding mechanisms mounted on said rotatable frame, said 85 adjusting mechanism being adjustable as aforesaid to position the drill mechanism to drill parallel horizontal holes and parallel vertical holes at either side of said base.
43. In a drilling apparatus, a portable base, a frame mounted on said base for rotation about an axis extending longitudinally of said base, mechanism including supporting means swingable relative to said base for adjusting said frame into different elevated positions relative to said base and having a range of adjustment in excess of 180° , drill rod rotation and feeding mechanisms mounted on said rotatable frame, said supporting means being adjustable as aforesaid to position the drill mechanism to drill holes in 90 positions between a position near the ground surface and a position a substantial distance above said base, and a motor on said base for driving said rotation mechanism irrespective of the adjusted position of said frame relative to said base.
44. In a drilling apparatus, a portable base, 95

5 a frame mounted on said base for rotation about an axis extending longitudinally of said base, mechanism for adjusting the elevation and lateral position of said frame relative to said base while said frame is maintained against bodily movement in a direction longitudinally of said base, drill rod rotation and feeding mechanisms mounted on said rotatable frame, said adjusting mechanism being adjustable as aforesaid to 10 position the drill mechanism to drill parallel horizontal holes and parallel vertical holes at either side of said base, and a motor on said base for driving said rotation mechanism irrespective of the adjusted position of said frame 15 relative to said base.

45. In a drilling apparatus, a portable base, a frame mounted on said base for rotation about an axis extending longitudinally of said base, mechanism including supporting means swingable relative to said base for adjusting said frame into different elevated positions relative to said base, drill rod rotation and feeding mechanisms mounted on said rotatable frame, said supporting means being adjustable as aforesaid to position the drill mechanism to drill holes in a position near the ground surface and in a position a substantial distance above said base and in intermediate positions in advance of said base, and a motor on said base for driving said 20 rotation mechanism and for operating said feeding mechanism irrespective of the adjusted position of said frame relative to said base.

46. In a drilling apparatus, a portable base, a frame mounted on said base for rotation about an axis extending longitudinally of said base, mechanism for adjusting the elevation and lateral position of said frame relative to said base while said frame is maintained against bodily movement in a direction longitudinally of said 30 base, drill rod rotation and feeding mechanisms mounted on said rotatable frame, said adjusting mechanism being adjustable as aforesaid to position the drill mechanism to drill parallel horizontal holes and parallel vertical holes at either 35 side of said base, and a motor on said base for driving said rotation mechanism and for operating said feeding mechanism irrespective of the adjusted position of said frame relative to said base.

50. 47. In a drilling apparatus, a portable base, a swiveled drill head carrying a boring tool and including feeding and rotating means for the tool, and an adjustable supporting structure for said drill head for adjusting the boring tool, while the latter is maintained against bodily movement in a direction longitudinally of said base, into parallel vertical boring positions, including a position between the sides of the base, and into parallel horizontal boring positions, said 55 drill head swiveled about an axis extending longitudinally of the apparatus.

48. In a drilling apparatus, a portable base, a drill head swiveled for rotation about a longitudinal axis, an adjustable supporting structure of said drill head for adjusting said head into different elevated positions relative to said base, a drilling tool carried by said drill head, drill rotation mechanism carried by said drill head for rotating the drilling tool, pressure fluid operated feeding means carried by said drill head for feeding the drilling tool during rotation thereof, a pump carried by said base for supplying fluid under pressure to said feeding means, a motor on said base for operating 60 said pump, said drill head adjustable into afore- 65 said

said elevated positions relative to said motor and pump, and adjustable connections driven by said motor for driving said rotating mechanism, said pump being operative to supply fluid under pressure to said feeding means and said connections operative to drive said rotation mechanism irrespective of the elevated position of the drill head relative to said base. 70

49. In a drilling apparatus, a portable base, an arm pivotally mounted on said base at one end and midway between the sides thereof to swing relative thereto in transverse vertical planes in advance of said base about an axis extending longitudinally of said base, said arm being swingable about said axis into horizontal positions 15 wherein the outer extremity thereof extends laterally from either side of the base, and a drilling tool carried at the outer extremity of said arm and adjustable with said arm in any desired drilling position between drilling positions beyond the sides of said base when said arm is in aforesaid horizontal positions. 20

50. In a drilling apparatus, a portable base, an arm pivotally mounted on said base at one end and midway between the sides thereof to swing 25 relative thereto in transverse planes in advance of said base about an axis extending longitudinally of said base, said arm being swingable about said axis into horizontal positions wherein the outer extremity thereof extends laterally 30 from either side of the base, and a drilling tool swivelly mounted on the outer extremity of said arm, the swivel axis of said drilling tool in any position of said arm about said longitudinal axis remaining always parallel to a common straight 35 line.

51. In a drilling apparatus, a portable base, an arm pivotally mounted on said base at one end and midway between the sides thereof to swing relative thereto in transverse planes in advance 40 of said base about a longitudinal axis, said arm being swingable about said axis into horizontal positions wherein the outer extremity thereof extends laterally from either side of the base, and a drilling tool swiveled on the outer extremity 45 of said arm to swing about an axis parallel with the arm axis.

52. In a drilling apparatus, a portable base, a frame rotatable about a longitudinal axis, an adjustable supporting structure on said base for 50 adjusting said frame into different elevated positions relative to the base, a support hinged on said rotatable frame to swing relative thereto, and a drilling tool mounted on said hinged frame.

53. In a drilling apparatus, a portable base, a 55 drilling tool, and adjustable supporting means on said base for supporting said drilling tool for adjustment in vertical planes extending transversely of said base into parallel vertical drilling positions, including a position between the sides 60 of the base, and parallel horizontal drilling positions, said supporting means including a swiveled frame rotatable about a horizontal axis extending longitudinally of said base for supporting said tool for adjustment into aforesaid 65 horizontal and vertical drilling positions and said supporting means being adjustable about an axis distinct from aforesaid axis and extending longitudinally of said base to adjust said tool in aforesaid parallel positions. 70

54. In a drilling apparatus, a base, a boring tool swivelly mounted on said base on an axis extending longitudinally of said base, and adjustable supporting means for said boring tool for adjusting the swivel axis of the latter verti- 75

cally relative to the base to position said boring tool in parallel horizontal boring positions for drilling in advance of said base, said supporting means being adjustable to move the swivel axis 5 of said boring tool to position said boring tool through a relatively wide range of such adjustments including a relatively low horizontal boring position adjacent the ground surface.

55. In a drilling apparatus, a base, a boring tool, and adjustable supporting means for said boring tool for adjusting the latter vertically relative to the base into parallel horizontal boring positions for drilling in advance of said base, said supporting means being adjustable to position 10 said boring tool through a relatively wide range of adjustments relative to said base in any desired horizontal boring position between a relatively low horizontal bottom boring position adjacent the ground surface and a relatively high 15 horizontal top boring position a substantial distance above said base, and a motor on said base and relative to which said boring tool is adjustable for driving said boring tool in any of afore- said adjusted positions.
56. In a drilling apparatus, a portable base, a frame mounted on said base for rotation of more than 180° about an axis extending longitudinally of said base, mechanism for adjusting said frame into different elevated positions relative to said 20 base, drill rod rotation and feeding mechanisms mounted on said rotatable frame and adjustable with the latter as aforesaid into parallel horizontal drilling positions and parallel vertical drilling positions, and a motor on said base for driving said rotation mechanism irrespective of the 25 adjusted position of said frame relative to said base.

57. In a drilling apparatus, a portable base, a frame mounted on said base for rotation of more than 180° about an axis extending longitudinally of said base, mechanism for adjusting the elevation and lateral position of said frame relative to said base, said frame being adjustable by said mechanism across the end of said base from one 30 side thereof to the other while said axis always extends longitudinally of said base, drill rod rotation and feeding mechanisms mounted on said 35 rotatable frame, and a motor on said base for

driving said rotation mechanism irrespective of the adjusted position of said frame relative to said base.

58. In a drilling apparatus, a portable base, a frame mounted on said base for rotation of more than 180° about an axis extending longitudinally of said base, mechanism for adjusting said frame into different elevated positions relative to said base, drill rod rotation and feeding mechanisms mounted on said rotatable frame, and adjustable 10 with the latter as aforesaid into parallel horizontal drilling positions and parallel vertical drilling positions, and a motor on said base for driving said rotation mechanism and for operating said feeding mechanism irrespective of the 15 adjusted position of said frame relative to said base.

59. In a drilling apparatus, a portable base, a frame mounted on said base for rotation about an axis extending longitudinally of said base, 20 mechanism for adjusting the elevation and lateral position of said frame relative to said base, said frame being adjustable by said mechanism across the end of said base from one side thereof to the other while said axis always extends longitudi- 25 nally of said base, drill rod rotation and feeding mechanisms mounted on said rotatable frame, and a motor on said base for driving said rotation mechanism and for operating said feeding mechanism irrespective of the adjusted position 30 of said frame relative to said base.

60. In a drilling apparatus, a base, a drilling tool, and adjustable supporting means on said base for said drilling tool for supporting the latter in advance of said base, said supporting means 35 embodying means for adjusting said drilling tool relative to said base through a series of parallel drilling positions, and means distinct from said adjusting means for adjusting said drilling tool into different angular positions relative to said base, the longitudinal axis of said drilling tool in all of aforesaid positions lying in a common vertical plane extending transversely of said base, and a motor mounted on said base and relative 40 to which said drilling tool is adjustable for driving said drilling tool irrespective of its adjusted 45 position.

HARRY C. JOHANSEN.
